(57) **CLAIM**

The ornamental design for a grip for an aircraft, as shown and described.

DESCRIPTION

FIG. 1 is a rear, right perspective view of a grip for an aircraft in accordance with our design.

FIG. 2 is a front, left perspective view thereof.

FIG. 3 is a top plan view thereof.

FIG. 4 is a rear elevation view thereof.

FIG. 5 is a left side elevation view thereof.

FIG. 6 is a right side elevation view thereof.

FIG. 7 is a front elevation view thereof; and,

FIG. 8 is a bottom plan view thereof.

The drawings show a grip for an aircraft specific to left-hand applications. The grip for an aircraft specific to right-hand applications is a mirror image thereof and therefore not shown.
